UNITED STATES PATENT OFFICE.

JAMES HENLY FRIER, JR., OF WEBSTER GROVES, MISSOURI.

DESIGN FOR A TOY HOUSE.

Application filed September 19, 1928. Serial No. 28,205. Term of patent 14 years.

To all whom it may concern:

Be it known that I, JAMES HENLY FRIER, Jr., a citizen of the United States, residing at Webster Groves, St. Louis County, and State of Missouri, have inventel a new, original, and ornamental Design for a Toy House, substantially as shown in the accompanying drawing.

The drawing is a perspective view showing my new design of toy house. The linings for colors indicate contrasting colors.

I claim:

The ornamental design for a toy house; substantially as shown.

JAMES HENLY FRIER, JR.
